UNITED STATES PATENT OFFICE.

HERMAN L. GREVE, OF NEW YORK, N. Y., ASSIGNOR TO INTERNATIONAL MAILING
TUBE & WRAPPER COMPANY, A CORPORATION OF NEW YORK.

MAILING-WRAPPER.

1,207,900.

Specification of Letters Patent. Patented Dec. 12, 1916.

Application filed October 28, 1914. Serial No. 868,546.

To all whom it may concern:

Be it known that I, HERMAN L. GREVE, a citizen of the United States, and a resident of New York city, borough of Brooklyn, in the county of Kings and State of New York, have invented certain new and useful Improvements in Mailing Wrappers, of which the following is a specification.

This invention relates to mailing wrappers used for mailing photographs, magazines, books or similar articles, particularly of the type described and claimed in my prior Patents Numbers 1,092,209 and 1,092,210.

The principal object of my invention is to provide a wrapper of this character with means for easily and securely fastening the flaps together when the wrapper is set up.

The various further objects and advantages will more fully appear from the accompanying description and the features of novelty will be particularly pointed out in the claims.

In the drawings illustrating this invention: Figure 1 is a perspective view illustrating the wrapper as set up. Fig. 2 is a development of the wrapper, one of the flaps being shown turned over. Fig. 3 is a perspective view of a modified form of wrapper in which the fasteners are attached to the side instead of the end flaps. Fig. 4 is a development of the wrapper illustrated in Fig. 3, one of the end flaps being shown turned over.

Referring in detail to the drawing, particularly to Figs. 1 and 2, the improved mailing wrapper is preferably formed of stiff, fibrous material such as paste board and the like comprising a bottom or body portion 10, from which extend the end flaps 11, and side flaps 12. Between the body portion and the end flaps, there may, if desired, be formed the upstanding end walls 13 and likewise, if desired, between the body portion and the side flaps may be formed the upstanding end walls 14. The side flaps are formed with notches 15 at their meeting edges which divide the flaps into sections 16 and 17 which alternately overlie and underlie the corresponding opposing sections. So far the construction is substantially the same as in my prior patents above referred to.

I will now describe the improved means whereby the flaps are reliably and securely fastened to each other with the utmost ease.

Attached to each of the end flaps 11 is a fastener 18 having one or more tongues 19 preferably extending flatwise of the material over which register the perforations 20 formed in the side flaps. When the wrapper is set up and the flaps 12 are interlocked in place as shown in Fig. 1, the tongues 19 are exposed through the perforation 20 as clearly appears from the right end of the wrapper in Fig. 1. These tongues may then be readily grasped by the fingers and bent over in the position shown in the left of Fig. 1, thus securely locking the side flaps to the end flaps. Preferably, the perforation 20 is formed with the inclined walls 21, located preferably at the outer side of the perforation or that side which is nearest to the end edge of the body portion, over which walls the tongues 19 are bent in angular relation to each other, thus affording still greater security to the fastening.

Referring to the modification illustrated in Figs. 3 and 4, the fasteners 25 and 26 are respectively attached directly to the sections 16 and 17 to the corresponding side flaps 12, while the perforations 27 and 28 are formed in the flap sections 16 and 17 respectively opposing the fasteners 25 and 26. The tongues 29 of the fasteners extend in the direction of the width of the flaps and are of a length such that the ends thereof are exposed so as to be readily manipulated by the fingers when the wrapper is set up, as shown in Fig. 3. The angular walls 30 of the perforations are preferably on the side nearest to the side edges of the flaps, so as to dispose the retaining means in the direction best calculated to afford security against accidental opening of the wrapper.

It will thus be seen that I have provided a fastening means for the type of wrapper disclosed in my prior Patents Numbers 1,092,209 and 1,092,210, which specially cooperates with the form of interlocking flaps to secure the same firmly in place with the utmost ease. As the perforations are formed with the inclined shoulders on the side nearest the edge of the body portion, the side flaps are stretched taut longitudinally and are held from movement laterally. This particularly cooperates with the interlocking form of flap as this form of flap effectually prevents the sagging or opening of the flaps at their middle, and thus in connection with the simple and easily operable fastener de-

scribed forms a highly satisfactory securing arrangement for the wrapper.

It will be noted, moreover, that the fastener engaging the inclined shoulder tends 5 to hold the side flaps in proper engagement with each other at the vertices of their notches.

Having thus described my invention, I claim as new and desire to secure by Letters 10 Patent:

1. A mailing wrapper having a body portion, end flaps and interlocking side flaps, said side flaps having portions overlapping each other, said overlapping portions being formed with registering perforations and fasteners attached to the end flaps having portions which may be grasped through the perforations and divergently bent to engage the side flaps to hold the latter in place when set up, said perforations being of sufficient width to permit passing of the fingers therethrough to grasp the tongues before they are bent over.

2. A mailing wrapper having a body portion, end flaps and interlocking side flaps, said side flaps having portions overlapping each other, said overlapping portions being formed with registering perforations of substantial area, and fasteners attached to the end flaps, said fasteners being each formed with a tongue extending flatwise of the material and of a substantially smaller length than the perforation whereby the tongue may be grasped through the registering perforations and bent over the side flap to hold the same in place when set up.

3. A mailing wrapper having a body portion, end flaps and interlocking side flaps, said side flaps having portions overlapping each other, said overlapping portions being formed with registering perforations of substantial area, and fasteners attached to the end flaps, each fastener being formed with a plurality of tongues extending flatwise of the material and of a substantially smaller length than the perforation whereby the tongue may be grasped through the regis-

tering perforations and bent over the side flap to hold the same in place when set up.

4. A mailing wrapper having a body portion, end flaps and interlocking side flaps, said side flaps having portions overlapping each other, said overlapping portions being formed with registering perforations having converging angularly disposed walls, and fasteners attached to the end flaps, each fastener having a tongue adapted to be grasped when the perforation registers thereover to be bent over the angularly extending wall.

5. A mailing wrapper having a body portion, end flaps and interlocking side flaps, said side flaps having portions overlapping each other, said overlapping portions being formed with registering perforations having a plurality of converging angularly disposed walls and fasteners attached to the end flaps, each fastener having a plurality of tongues extending flatwise of the material of the end flap, said tongues adapted to be grasped when the perforation registers thereover to be bent divergently over the angularly extending walls.

6. A mailing wrapper having a body portion, end flaps and interlocking side flaps, said side flaps having portions overlapping each other, said overlapping portions being formed with registering perforations having a plurality of angularly disposed walls at the side of the perforation nearest the end edge of the body portion, fasteners attached to the end flaps, each fastener having a plurality of tongues extending flatwise of the material, said tongues adapted to be grasped when the perforation registers thereover to be bent divergently over the angularly extending walls.

Signed at New York city, in the county of New York and State of New York, this 28th day of September, A. D. 1914.

HERMAN L. GREVE.
